PACKING MATERIAL

Michael R. Cannon, State College, Pa., assignor to
Scientific Development Co., State College, Pa.,
a corporation of Pennsylvania

Application March 2, 1948, Serial No. 12,490

7 Claims. (Cl. 261—95)

This invention relates to packing material for use in phase reaction devices. More particularly, it relates to packing units made of sheet material such as sheet metal, and upon the surface of which a substituent of one phase may be brought into intimate contact with a substituent of the same or of a different phase.

Generally speaking, the invention provides packing material which comprises units of thin sheets or sections of metal, each unit being shaped so that it does not entirely lie within the same plane. Each surface or side of the unit preferably has a plurality of perforations extending therethrough, each perforation on one side being usually sunken or recessed with respect to the adjacent surrounding surface and on the opposite side being surrounded by a protrusion or burr extending outwardly from the surface of the metal. The units are further characterized by having at least about 100 perforations or openings per square inch. While the perforations in each unit may be located in any arrangement, random or otherwise, for convenience in forming they are preferably grouped in adjacent rows, and each row on the said first side of each unit may or may not be separated from each adjacent row by an outwardly extending ridge.

The invention may be better understood by referring to the accompanying drawings in which illustrative embodiments are shown and in which: Figs. 1-9 are enlarged perspective views of variously shaped packing units; and Fig. 10 is a broken out view of the units as they appear in a phase reaction device or column.

The shape of the packing units is variable. They may, for example, be cylindrical in shape, or semi-cylindrical, or have the shape of any other part of a cylinder. They may have a saddle shape, an angle shape of relatively simple form, the shape of an S, a trough shape, or a multiple trough shape. They may also have a spiral shape, a spherical, conoidal, or pyramidal shape, or the shape of any part of a sphere, cone, or pyramid. Some of these shapes are illustrated in the drawing. Thus, in Fig. 1 is shown a semi-cylindrical device 10 of relatively short length and having transverse rows 11 of openings 12. The openings are sunken with respect to the surface of the device, i. e. the metal area 13 immediately surrounding the opening slopes downwardly toward the opening from the adjacent metal area 14. Intermediate adjacent rows of the openings are transverse ridges or ribs 15. On the underside 16 of the unit are protrusions or burrs 17 which are formed when the openings 12 are made in the

2

unit. The openings on both sides of the unit may be circular, as shown, or irregular.

When a quantity of the units is packed in a phase reaction device such as a distillation, extraction, or absorption column, the burrs 17 serve to space one unit from another in contact therewith and so permit fluids to flow through the packed mass. A spacing effect is also obtained as a result of the geometric shape of the unit as a whole.

In Fig. 2 is shown another unit 19 of semi-cylindrical form but of somewhat greater length than the unit of Fig. 1. The holes 20 of this unit have a more or less rectangular shape. In this case the rows 21 of the openings extend longitudinally of the unit and are separated by the longitudinal ridges 22. Each opening is sunken, as indicated at 23, with respect to the metal area 24 immediately surrounding it, and the rows of openings have a sunken or recessed appearance relative to the adjacent ridges. The openings terminate in protrusions or burrs 25 on the underside of the unit.

A V-shaped rectangular appearing unit 21 is shown in Fig. 3. It has transverse rows 28 of openings 29 alternating with transverse ridges 30. Each opening is sunken in the upper side of the unit and terminates in a burr 31 on the underside of the unit.

In Fig. 4 is shown a unit 33 which was originally square shaped but in which one pair of opposite corners 34, 35 are bent upwardly and the other pair of corners 36, 37 bent downwardly. Openings 38 are shown as having a circular shape, and as in the devices previously described, are arranged in the form of rows 39 alternating with ridges 40. Each opening terminates on the under surface of the unit in a burr 41.

A unit 43 of tubular shape is shown in Fig. 5 and, as may be seen, comprises a spirally wound perforated ribbon or strip 44. Openings 45 are arranged in spirally shaped rows 46, each of which is separated by spirally shaped ridges 47. In this form of unit the protrusions 48 appear on the outer surfaces of the device.

Fig. 6 illustrates a device 50 having what may be termed a semi-S shape. The openings 51 are arranged in rows 52, as in the previous cases, but there are no ridges adjacent each row. Each opening has a corresponding burr 53 on the opposite side of the unit.

An S-shaped unit 55 is shown in Fig. 7 on a more enlarged scale than in the preceding figures. As in the previous cases, the openings 56 are arranged in rows 57 and have corresponding

protrusions 58 on the opposite side of the unit. Ridges 59 alternate with the rows of openings.

A variation of the semi-cylindrical unit of Fig. 2 is shown in Fig. 8, one of the edges 61 of the unit being bent to one side. Openings 62 are arranged in rows 63 and have the protrusions 64. The ridges, however, are absent. Fig. 9 represents still another variation of Fig. 2, a pair of corners 65, 66 being bent to one side, as shown, and the usual rows of openings 67 terminating in the protrusions 68.

In general, the shape of the units may partly be determined by the use to which they are put. For example, curved shapes may cause less pressure drop than angular shapes, so that the former will be desirable where pressure drop is important. Where pressure drop is not important, as, say, in high pressure work, units of other shapes are suitable, preferably those that are less expensive to manufacture.

Fig. 10 illustrates a mass of units, such as those shown in Fig. 2, in a column 70. The latter may be distillation column, or an extraction tower, or an absorption column, or other phase reaction device. It may serve to bring into contact with each other pairs of substances for liquid-liquid phase contacting, or liquid-gas contacting, or gas-gas, liquid-solid, or gas-solid contacting. More than two substances may be brought into contact with one another at the same time.

The size of the packing units is also variable, but generally they are of comparatively small size, being especially suitable for precision work. For this purpose they are preferably about $\frac{1}{8}$ to about $\frac{1}{2}$ inch wide and about $\frac{1}{8}$ to about $\frac{1}{2}$ inch long. The surface area of one side of such a unit should be at least about $\frac{1}{64}$ square inch and may vary up to about $\frac{1}{4}$ square inch. The thickness of the foregoing sizes may range from about 0.001 to about 0.02 inch, depending to some extent upon the kind of metal employed. In this connection, units of the foregoing range of thickness are considered to be made of "thin" material. For stainless steel units the thickness may be as low as 0.001 inch. Nickel units of about 0.003 inch thickness have been found to be satisfactory. Other suitable metals for the units include brass, copper, aluminum, various alloys, etc. The choice of metal, of course, will depend upon its cost and upon the materials to be brought into contact with each other. For larger phase reaction devices the units may have a major dimension, i. e. the length, of up to about 2 inches with the other dimensions proportional to it.

The number of perforations or openings in each unit is variable, but they should be sufficient to cause liquids to readily wet, or crawl up, the units. As will be appreciated, when a liquid touches one side of a unit, it tends to transfer itself through the openings and around the edges of the unit and wet the other side, due to the effect of surface or interfacial tension. The more openings there are, the more readily the entire area of the unit will become wetted. On a numerical basis, there should be at least 100 openings per square inch, preferably about 1000, and there may be as many as 1600.

As indicated, the spacing of one unit with respect to others in a packed mass of the units may be a function of both the shape of the unit and of the presence of the burrs. The first of these factors is evidenced by the fact that all of the units have their surface area distributed in at least two planes. The spacing effect may, however, be substantially the result of one or the

other of these factors. For example, the burrs may be so large as to act as the sole spacing parts; or in some cases the shape of the unit may be made sufficiently irregular as to enable the unit to adequately space itself, the burrs and openings being eliminated. An example of the latter shape is a unit in the form of an S.

A significant advantage of the packing units, as above described, is that they are considerably less expensive than conventional packing materials such as those made from metal screen material, i. e., so-called wire cloth, or from single or multiple wire coils. The cost of the present units, for example, may run from about one-fifth to one-seventh as much as the conventional materials referred to. In addition, the units are at least equal, or superior, to conventional materials. In respect to the wire coils, the present units have the advantage of being more readily wetted, and hence their efficiency tends to be greater. In regard to metal screen material, the present units are characterized by having a greater contact area since the metal displaced to form the perforations still remains as a part of the packing; also, the displaced metal, which is in the form of a burr, acts as a spacer and so prevents the units from packing so densely as to hinder the passage of fluids therebetween.

In the light of the foregoing description, the following is claimed:

1. Packing material for enabling material of one phase to be brought into intimate contact with material of another phase consisting of individual units of thin sheet metal, each unit having its surface area distributed in at least two planes, the surface area of one side of each unit varying from about $\frac{1}{64}$ to about $\frac{1}{4}$ square inch, each unit having a plurality of openings therein with said openings occurring in at least two planes of the unit, each opening on one side of each said unit being sunken below the level of the adjacent surface while on the other side of the unit the opening is substantially surrounded by a protrusion or burr, said burrs together with the geometric shape of each said unit aiding to space one unit from another when the units are packed together in bulk, and the number of openings in each said unit varying from about 100 to about 1600 per square inch.

2. Packing material for enabling material of one phase to be brought into intimate contact with material of another phase consisting of individual units of thin sheet material, the surface area of one side of each unit varying from about $\frac{1}{64}$ to about $\frac{1}{4}$ square inch, each unit having a plurality of openings therein, each opening on one side of each said unit being substantially surrounded by a protrusion or burr, said burrs aiding to space one unit from another when the units are packed together in bulk, and the number of openings in each said unit varying from about 100 to about 1600 per square inch.

3. Packing material for enabling material of one phase to be brought into intimate contact with material of another phase consisting of individual units of thin sheet material, each unit having its surface area distributed in at least two planes, the surface area of one side of each unit being at least $\frac{1}{64}$ square inch, each unit having a plurality of openings therein distributed in at least two planar surfaces of the unit, each opening on one side of each said unit being substantially surrounded by a protrusion or burr, said burrs together with the geometric shape of each said unit aiding to space one unit from another

when the units are packed together in bulk, and the number of openings in each said unit being at least 100 per square inch.

4. Packing material for enabling material of one phase to be brought into intimate contact with material of another phase consisting of individual multiplanar units of thin sheet material, the surface area of one side of each unit being at least $\frac{1}{64}$ square inch, each unit having a plurality of openings therein, each opening on one side of each said unit being substantially surrounded by a protrusion or burr, said burrs aiding to space one unit from another when the units are packed together in bulk, and the number of openings in each said unit being at least 15 100 per square inch.

5. Packing material upon the surface of which a substance of one phase may be contacted with a substance of the same or a different phase which comprises units of thin sheets of metal, each unit having multiplanar surfaces, a plurality of perforations extending through each unit and distributed throughout said surfaces, each perforation on one side being surrounded by an 20 25 outwardly extending burr and the number of said perforations being at least 100 per square inch, said units being adapted to be packed within a confined space so that each unit comes into contact with other units, and said burrs aiding to space one unit from another in contact therewith and so render a packed mass of the units relatively porous.

6. Packing material upon the surface of which a substance of one phase may be contacted with a substance of the same or a different phase which comprises multiplanar units of thin sheets of metal, each unit having a plurality of perforations extending therethrough and distributed in various planar surfaces of the unit, each 30 35 40 perforation on one side being surrounded by an

outwardly extending burr and the number of said perforations being at least 100 per square inch, and said units being adapted to be packed within a confined space so that each unit comes into contact with other units.

7. Packing material for enabling material of one phase to be brought into intimate contact with material of another phase consisting of individual units of thin sheet metal, each unit having its surface area distributed in at least two planes, the surface area of one side of each unit varying from about $\frac{1}{64}$ to about $\frac{1}{4}$ square inch, each unit having a plurality of protrusions therein distributed in at least two planar surfaces of the unit, each said protrusion terminating in an opening, said units being adapted to be packed within a confined space so that each unit comes into contact with other units, said protrusions together with the geometric shape of each said unit aiding to space one unit from another in contact therewith and so render a packed mass of the units relatively porous, and the number of openings in each said unit being at least 1000 per square inch.
